UNITED STATES PATENT OFFICE.

EDWARD L. COFFIN, OF MINNEAPOLIS, MINNESOTA.

GAME APPARATUS.

SPECIFICATION forming part of Letters Patent No. 517,262, dated March 27, 1894.

Application filed June 22, 1893. Serial No. 478,421. (No model.)

To all whom it may concern:

Be it known that I, EDWARD L. COFFIN, a citizen of the United States, residing at Minneapolis, in the county of Hennepin and State 5 of Minnesota, have invented certain new and useful Improvements in Game Apparatus; and I do hereby declare the following to be a full, clear, and exact description of the invention, such as will enable others skilled in the 10 art to which it appertains to make and use the same.

My invention has for its object to provide an entertaining game apparatus for parlor use.

To this end, the invention consists of certain apparatus and method of playing, which 15 will be hereinafter fully described, the novel features of which will be defined in the claims.

In the accompanying drawing, the single figure represents the game apparatus.

20 This apparatus comprises a board or ground field A, having marked thereon a stepped course, which as shown, is indicated by star marks in black, the said star marks, as shown, being arranged to form a square or parallelogram with diagonal lines having a sun-mark a at their intersection or at the center of the square. The star-marks are distinguished into common and honor values. The small star marks a' are all of like value, as denot- 25 ing one step in the course; but the large star- marks a², at the corners of the course, are of a special or honor value, as will more fully hereinafter appear. The large star-marks outside the rectangular course, indicated by 30 the letter a³, serve to point out the proper positions for entering the movable men manipulated by the player. These marks a³, may for distinction be hereinafter called, the star pointers. The proper positions for the re- 35 40 spective players are opposite these star-pointers a³.

B represents the movable men or pieces, which for convenience, may be hereinafter called the star-men. Of these star-men, five, 45 as shown, are provided for each player; four of which are of a common size and marked b; and one of which, marked b', is of larger size, and has a special point value in the scoring, as will hereinafter appear.

50 The several groups of star-men B, are distinguished in any suitable way, as by differ-

ent coloring, indicated on the drawing by different shadings.

It has already been stated, that the corner stars a² of the course, have not only the ordinary one step value of the small star-marks a', but have certain special or honor values in the course, with respect to the different players. These honor values depend on the position of the respective corner star-marks 55 a², with respect to the players, as long as any of the particular player's star-men B remain unentered; and depend upon the position of the rearmost star-man of any particular player, after all of his star-men have been entered. 60 These several honor values of the corner star-marks a², are named in script, on the drawing, at the corners of the board. The first corner star-mark a², to the right of the player, if any of his men remain unentered, would 65 be his first star. The next corner star-mark a², would be his second star. The third corner star-mark a², would be his crown; and the fourth corner star-mark, would be his double crown. After all the star-men B, of any particu- 70 lar player have been entered, the honors be- 75 come cumulative toward and upon the final or double crown star-mark a². For instance, if the player's rearmost man be past that player's original first corner star-mark a², then his origi- 80 nal second star, will be treated as his first star, the original crown star as his second star; and the original double crown, will be treated 85 both as the crown and double crown star. So the honors accumulate on the double crown star-mark, until, if the player's rearmost man (all being entered) be beyond his original crown star, the original double crown would be treated as first star, second star, crown and double crown.

90 In addition to the board, marked as de- 95 scribed, and the movable star-men, the game apparatus comprises a deck of cards distin- 95 guishing common and honor combination course values. The deck is preferably com- posed of twenty-four cards, sixteen of which are marked to denote common course values, from one to five; three of which are marked, as with the word "Combination," to distin- 100 guish the same as combination honor cards, and also with the word "One," to indicate their common value, when not used with honor

cards; and five honor cards, marked, respectively, five, first star; ten, second star; fifteen, crown; twenty, double-crown; and court. The numbers 5, 10, 15 and 20, printed on these honor cards, indicate their common or course value, when in the absence of combination cards from the hand, it is not possible to use the same, according to their honor value.

In the drawing, four full hands of six cards each, properly marked, are shown in the positions, with respect to the board A, which would be occupied by the players. These hands of cards are indicated by the letter C. The cards, it will thus be seen, differ in course value, and determine the movements of the star-men.

Method of play.—While it is obvious, that the apparatus is adapted for manipulation under various methods of play, to form interesting games, I prefer and have especially designed the same for a point or score system of play; and have arbitrarily fixed the winning or game number at thirty-seven points. On account of certain superficial resemblances in the manner of scoring, I have called the game "star cinch." The game is designed for four persons, although it may be played by three. The players take positions; all the cards are dealt out, one at a time to the respective players; and the first player to the left of the dealer begins the play; and the deal passes from the right toward the left;—all exactly as in whist. The star-men B are entered on the course, one at a time, at the star-pointers, by the respective players, and are moved on the course toward the right, according to the course value of the common or combination honor cards, from which the play is made in the particular hand. The effort is to enter all the star-men and move the same entirely around the course onto the particular player's double crown star-mark a^2 , to-wit; the corner star-mark to his left, and thence, by way of the diagonal line, into the court, directly at the player's front and between the course and the central sun. The corners or honor star-marks a^3 are points or positions of safety for the star-men. From all the other, or common value star-marks a' , an advance player's star-man, or star-men stacked thereon, may be overtaken, by a subsequent player's star-man, or stack of star-men, and be thrown back off the course to the unentered or star-pointer position. There are no blockades. Stacking of several star-men on a single star-mark and the movement of the entire stack as a single man, is permissible. This gives hope of rapid progress; but runs the risk of the entire stack being knocked off the course and returned for re-entry at the star-pointer. Suppose the cards to have been dealt to four players and the hands to be as shown in the drawing, the man to the right having been the dealer. The cards must be used, first of all to enter the men; and at the time of entry, the particular

man entered may be moved as far as indicated by the course value of the card from which the play was made. After all the star-men of any player have been entered, any one man or stack of men may then be moved on the course, according to the course value of the card. If the player have only cards of common value, as two, three, four, five, &c.; or even have honor cards, as first star, second star, crown and double crown, without the presence of a combination card, in his hand, he is confined to the simple or course values numbered at the top of the card. If, however, the hand contain one or more combination cards, together with one or more honor cards, then the player can avail himself of the honor value of his honor cards in succession. For example, in the drawing, the first hand having a combination card, together with three honor cards, could first play from either of said three honor cards. Playing according to highest value, the said first player would first use the double crown card, entering one of his men and moving the same on the course to the double crown or corner star at his left. On his next play, he would enter a man and use his second value honor card "second-star," moving his man on the course to the second corner star toward the right. On his third play, he would play from his single honor or first star card, entering his man and placing him on the first star to his right. Thereafter, he would have to play from the remaining three simple value cards, the combination card having a simple value of one step, as denoted at the top of the card. As the plays are made, the cards from which the plays are made, by each player, are turned down. The combination cards are held as long as any honor cards remain in the hand; as otherwise, the honor values of the honor cards cannot be utilized. In the foregoing stated order of play for the first hand, it has been assumed that the honor value star marks a^2 remain clear for the second and third plays of the first player; but if the same had been occupied by men belonging to some of the other players, it would not have been possible for the first player to have availed himself of the honor values of his honor cards. In that event, he would have been confined to the common value of his cards and would have played either from one of his low value cards, or played one of his honor cards at its common, instead of its honor value. He might also prefer to utilize the honor cards at their common values, in order to catch and set back another player's man. The particular player who happens to hold the high honor or court card, as the fourth player in the drawing, can place one of his men, directly into the court, whether before entered or not; and if he have a stack of men anywhere on the course, he can move the entire stack directly into the court. The presence of a combina- 130

tion card is not necessary, to utilize the value of the high honor or court card. After all the men of any given player have been entered, then as the rearmost man passes the first, second and third corner stars, the honors become cumulative on the fourth corner or double crown star, as hitherto noted. This progression of the corner star honors, may be readily remembered, by noting that any given player's, first honor star, is always in advance of his rearmost man, and the honors accumulate on the fourth corner or double crown, as rapidly as necessary, to give the full set. It will require at least five cards of the first hand, to enter all the men. It may require many more out of succeeding hands, according to the number of back-sets received by the star-men. After all the cards of the first hand have been played, the cards are redealt, the deal passing to the left, as in whist, and the play is continued. At the end of every third deal, the board is cleared, and all the star-men are restored to the star-pointer positions. This tends to even up the chances in spite of back-sets.

Score.—Each player works for himself, and the first to gain thirty-seven points, according to the following score, wins the game. The score is, of course, to be kept by one of the players or bystander. The score points are as follows: For every common value or small star-man b , overtaken and back-set by any given player, the said player is allowed two points. For every large star-man b' , or honor point value piece, overtaken and set back, the player is allowed five points. For every small star-man b , landed in the court, the player is allowed three points. For every large star-man b' , landed in the court, the player is allowed seven points. The points thus made continue to count up as in a game of cinch, until some one of the players reaches thirty-seven points and wins the game.

It is obvious, that a simpler form of game would be afforded by dispensing with the score and making the winning of the game to turn on first landing all the star-men of some one of the players in his court. The point or score game is, however, more interesting on account of the wider range and greater room for calculation.

By actual usage, I have demonstrated the entertaining character of this game.

In respect to the method of play, it should be further noted, that if any player lands all his star-men in his court, before his hand is played out, he turns down his cards and ceases to play until the remaining players have played out their hands or set of three hands, when, upon the board being cleared, he will again join in the play. It should also be noted, that with the exception of the "combination" cards, the hands are to be kept concealed. The combination cards are to be shown, so as to evidence title to play honor cards.

What I claim, and desire to secure by Letters Patent of the United States, is as follows:

1. A game apparatus, comprising a board marked with a stepped course of travel, movable pieces for traversing said course, and a deck of cards of varying value, certain of which are marked with common or individual values, and others of which are marked with both individual and combination values, substantially as and for the purpose set forth.

2. A game apparatus, comprising a board marked with a stepped course of travel, distinguishing common and honor value steps, movable pieces for traversing said course, and a deck of cards of varying value, certain of which are marked with common or individual values, and others of which are marked with both individual and combination values, substantially as described.

3. A game apparatus, comprising a board marked with a stepped course of travel, distinguishing common and honor value steps, movable pieces for traversing said course, certain of which represent common values and others of which represent honor values, and a deck of cards certain of which are marked with common or individual values, and others of which are marked with both individual and combination values, substantially as described.

In testimony whereof I affix my signature in presence of two witnesses.

EDWARD L. COFFIN.
